UNITED STATES PATENT OFFICE

117,797

DESIGN FOR A TOP

Adam Niedzinski, Nutley, N. J.

Application September 13, 1939, Serial No. 87,196

Term of patent 14 years

To all whom it may concern:

Be it known that I, Adam Niedzinski, a citizen of the United States, residing at Nutley, in the county of Essex and State of New Jersey, have invented a new, original, and ornamental Design for a Top, of which the following is a specification, reference being had to the accompanying drawing, forming part thereof.

I claim:

The ornamental design for a top, as shown.

ADAM NIEDZINSKI.
